CLAIM

The ornamental design for a display screen with transitional graphical user interface, as shown and described.

DESCRIPTION

1. Display screen with transitional graphical user interface

1.1 : Front

1.2 : Front

1.3 : Front

The outermost set of broken lines illustrate the display screen and the remaining broken lines illustrate portions of the transitional graphical user interface. None of the broken lines form part of the claimed design.

1 Claim, 3 Drawing Sheets
